UNITED STATES PATENT OFFICE.

FREDERIC SCHAEFER, OF PITTSBURGH, PENNSYLVANIA.

CONNECTING-BAR.

1,263,608.

Specification of Letters Patent. Patented Apr. 23, 1918.

Application filed December 18, 1916. Serial No. 137,618.

To all whom it may concern:

Be it known that I, FREDERIC SCHAEFER, a resident of Pittsburgh, in the county of Allegheny and State of Pennsylvania, have 5 invented a new and useful Improvement in Connecting-Bars, of which the following is a specification.

This invention relates to pressed metal connecting bars. It relates particularly to 10 connecting bars for use in connecting the brake levers of railway trucks, for use as push rods for brake cylinders, and for other similar purposes.

It is important in bars of this character 15 to have them constructed so that they possess a maximum strength for their weight, are reinforced in all of the usual weak points against bending or compressing strains, and further, are provided with extended bearings 20 for pivot pins or other pins to which they may be connected so as to reinforce them against wear by said pins. A bar of this general character is described in my co-pending application Serial No. 76,185, filed Feb- 25 ruary 4, 1916. The present application is a continuation in part of said prior application.

One of the objects of the present invention is to provide an improved connecting bar 30 structure having extended bearing surfaces for the pivot pins, which surfaces are formed without requiring excess thickness of metal in the entire body of the bar.

Other objects and advantages of the invention 35 will appear from the following specification.

The accompanying drawings illustrate an embodiment of the invention. The views of the drawings are as follows:

40 Fig. 1 is a plan view of a connecting bar embodying the invention.

Fig. 2 is a side elevation of the connecting bar, showing one end thereof in longitudinal cross section.

45 Fig. 3 is an enlarged longitudinal section on the line 3—3 of Fig. 2.

Fig. 4 is a vertical cross section on the line 4—4 of Fig. 2.

50 Fig. 5 is a cross section on the line 5—5 of Fig. 2.

Fig. 6 is a cross section on the line 6—6 of Fig. 2, showing a modification in the cross-sectional area of the bar.

55 The connecting bar comprises a body portion 1 formed of pressed metal, preferably

steel, having a cross section which may be of any one of the shapes shown in my prior application Serial No. 849,550, filed July 7, 1914.

Each end of the bar is provided with a 60 longitudinal slot 2 which forms pairs of oppositely disposed ears 3 whose outer ends are rounded, as indicated at 4. The ears 3 of each pair are substantially parallel with each other, the ears at opposite ends of the 65 bar being in line with each other. The pairs of ears at opposite ends of the bar are provided with one or more sets of oppositely disposed sets of pin eyes 5 for receiving pivot pins for connecting the bar to other parts. 70

It is important in structures of this kind that a relatively large bearing surface be provided for each of the pins so that the edges of the holes will not be readily worn by the pins and so that they will withstand 75 the stresses to which they are subjected. If the thickness of the metal is increased to provide the extra bearing surface, such material must be carried through the entire body of the bar and the weight of the bar 80 as well as its cost is increased. Further, if the holes or eyes are formed by drawing the metal in one direction the edge of the opening at which the drawing die enters will be rounded and the actual bearing surface of 85 the pin eye will not meet the requirements of practice without using metal of greater thickness than required for other parts of the bar.

In order to provide an extended bearing 90 surface of the required width without increasing the thickness of the metal employed, the metal in the vicinity of the openings is subjected to a die forming or forging operation. In forming the holes 5 the metal 95 is extruded, forming annular projections or protuberances 6 on the outside surfaces of the ears. The inner sides of the ears are forged or die pressed, as at 7, which reduces the thickness of the metal and forces it 100 outwardly, forming annular rings or protuberances 8 on the inside of the ears. The pin eyes thus have protuberances extending in both directions from the surface of the ears, these protuberances coöperating to produce an extended bearing surface of necessary width to meet the requirements of practice. The thinning of the metal in the vicinity of the eyes does not decrease the strength 105 of the ears below that required since there is 110

an ample factor of safety in the metal at this point, the greater strains on the bar being developed at other points.

It will be noted that the necessary bearing surface for the pin eyes is thus produced without requiring that the connecting bar be made out of heavier metal and without decreasing the strength of the bar below that required. The pin eyes and both sets of protuberances may be formed in a single die pressing operation, thus making the process very simple and inexpensive.

In order to reinforce the bar against bending strains, especially sidewise or in a direction parallel to the axis of the eyes and to further reinforce the bar at the junction of the ears 3 with the body portion 1, the metal of the side portions of said bar opposite the roots of the slots 2 is displaced laterally into arch form, as indicated at 10. The bulge or extension thus formed projects for a short distance lengthwise of the bar to either side of the root of the slot 2 and not only increases the beam effect and reinforces the bar against compression stresses but also reinforces it against bending stresses by changing the position of the neutral axis.

The connecting bar described is preferably made from a flat sheet or plate of forged or wrought steel which is first slotted at its opposite ends to form the ears 3. Either simultaneously with the slitting operation or before or after the same, each blank is subjected to a forging or die pressing operation to punch eye-holes 5 and forge the metal of the ears around said holes to reduce its thickness at the points 7 and form the protuberances 6 and 8 to produce the bearing surface for the pivot pins and reinforce the bar against wear thereby. The same pressing or forging operation forms the protuberances 10 opposite the roots of the slots 2. The blank is then bent or folded on its central longitudinal line to the proper hollow cross sectional shape, such as shown, for example, in Figs. 4 and 5, but which shape may be any of the forms shown in my prior application referred to.

After the bar has been forged, folded, and bent to the proper form the openings 5 which are directly opposite each other are trued by a reaming operation so as to produce a smooth bearing surface for the pivot pins.

Fig. 6 shows a cross section of a modified form of bar adjacent one of the pin eyes in the ears, the section being taken on the line 6—6 of Fig. 2. In this form the exterior of the bar is depressed, as at 9, in the die pressing or forging operation so that the ear at this central point is considerably thinner than at its edges, the metal being forced toward the edges in the die pressing operation. This provides a structure in

which the metal is increased in thickness at the points where it does the most good in resisting strains. The protuberances for forming the bearing surfaces for the pin eyes are formed in the same way as hereinbefore described.

The bar is simple and can be readily manufactured at a low cost. It has a maximum strength for its weight because it is reinforced at all of the usual weak points against bending or compressive strains, and especially against wear by the pivot pins. It meets the exacting requirements which are demanded for bars of this character and will not fail under the severe conditions encountered in railroad service.

It is to be understood that the structure shown is for purposes of illustration only and that other structures may be devised which come within the spirit and scope of the appended claims.

What is claimed is:—

1. A connecting bar, comprising a one-piece hollow body slotted at its end to form a pair of oppositely disposed ears, said ears being provided with oppositely disposed pin eyes, and protuberances around said eyes extending in both directions from the surface of the ears to form extended bearing surfaces, the metal adjacent said protuberances being thinner than the body of the ears.

2. A connecting bar, comprising a one-piece body having a pair of oppositely disposed ears at its end, said ears being provided with oppositely disposed pin eyes and with forged protuberances around said eyes extending in both directions from the body of the ears to increase the bearing surface.

3. A connecting bar, comprising a one-piece body having a pair of oppositely disposed ears at its end, said ears being provided with oppositely disposed pin eyes and with forged protuberances around said eyes extending in both directions from the body of the ears and in one direction beyond the surface of the bar to thereby provide an increased bearing surface about the eyes.

4. A connecting bar, comprising a one-piece body having a pair of oppositely disposed ears at its end, said ears being provided with oppositely disposed pin eyes, forged protuberances around said eyes projecting in both directions from the body of the ears and in one direction beyond the surface of the ears to thereby provide an increased bearing surface about the eyes, the metal of said ears being thinner near the central portions of the ears than at the edges.

5. A forged connecting bar, comprising a one-piece hollow body having a pair of oppositely disposed ears at its end, said ears being forged to reduce the thickness of the metal at certain points and provide oppo-

sitely disposed pin eyes with protuberances around said eyes extending in both directions from the body of the ears to increase the bearing surface around the eyes.

5 6. A forged connecting bar, comprising a one-piece hollow body having a pair of oppositely disposed ears at its end, said ears being forged to decrease the thickness at certain points and provide oppositely disposed pin eyes with protuberances around

the eyes extending in both directions from the body of the ears and in one direction beyond the surface of the bar to thereby increase the bearing surface around the eyes.

In testimony whereof, I have hereunto set my hand.

FREDERIC SCHAEFER.
